DOOR PANEL FOR A DISPENSING MACHINE

Francis A. Wittern, Des Moines, Iowa, assignor to Fawn Engineering Company, Des Moines, Iowa, a corporation of Iowa

Filed Feb. 19, 1969, Ser. No. 15,830

Term of patent 14 years

Int. Cl. D20—01

U.S. Cl. D52—3

Fig. 1

Fig. 2

Fig. 3

Fig. 4

Fig. 5

FIGURE 1 is a front perspective view of a door panel for a dispensing machine showing my new design;

FIGURE 2 is a rear perspective view;

FIGURE 3 is a side elevation view;

FIGURE 4 is a bottom plan view; and

FIGURE 5 is a top plan view.

The dotted line showing of a dispensing machine cabinet in FIGURES 1, 2 and 3 is for illustrative purposes only, and the dominant features of the design are shown in the full line portions thereof.

I claim:

The ornamental design for a door panel for a dispensing machine, substantially as shown and described.
